ADOLPH GLASER HUPFEL, OF NEW YORK, N. Y.

COMBINED HOP PRESS AND FILTER.

1,092,994.

Specification of Letters Patent. Patented Apr. 14, 1914.

Application filed September 27, 1911. Serial No. 651,507.

To all whom it may concern:

Be it known that I, ADOLPH G. HUPFEL, a citizen of the United States, and a resident of New York city, county of New York, and 5 State of New York, have invented a new and useful Improvement in Combined Hop Presses and Filters, of which the following is a specification, the principle of the invention being herein explained and the best 10 mode in which I have contemplated applying that principle, so as to distinguish it from other inventions.

The present invention relates more particularly to a combined hop press and filter 15 of the general construction illustrated in U. S. Letters Patent No. 903,574, issued to me Nov. 10, 1908, and comprising a rotatable receptacle having perforated walls, a movable head fitted therein, connections for 20 supplying the material to be operated upon to said receptacle, and means for respectively rotating said receptacle and actuating said movable head to compress such material, as desired. In order thus to supply 25 the mixture of hops and wort, constituting the specific material in mind, to the receptacle while rotating, a sleeve or gland is so mounted upon the drum intermediately between its ends as to permit free rotation of 30 the latter, the material being fed to the sleeve by a suitable exteriorly connected pipe, and passing from such sleeve into the drum's interior through openings in the portion of the drum's walls inclosed within the 35 sleeve.

The present improvements have as their object to decrease the friction and wear between the sleeve and the drum, as also to provide means whereby the hops are prevented from accumulating within the sleeve 40 so as to congest or choke up the latter.

To the accomplishment of these and related ends, said invention, then, consists of the means hereinafter fully described and 45 particularly pointed out in the claims.

The annexed drawings and the following description set forth in detail certain mechanism embodying the invention, such disclosed means constituting, however, but one 50 of various mechanical forms in which the principle of the invention may be used.

In said annexed drawings:—Figure 1 represents, partly in section, and partly in side elevation, a combined press and filter 55 embodying my present improvements; Fig. 2 is a transverse section thereof taken on

the line 2—2, Fig. 1; Fig. 3 is a similar transverse section taken on the line 3—3, Fig. 1; Fig. 4 is a section of a detail on the line 4—4, Fig. 2; and Fig. 5 illustrates a 60 modified construction.

The details of the mounting and operating mechanism associated with the rotary drum 1 are not of present interest, and furthermore are substantially the same as in the 65 patent above referred to. Preferably said drum is supported near each end on rollers 2, as usual in structures of the kind in hand. The one end of the drum is furthermore provided with a removable head 3 and 70 breech block 4, so as to permit the discharge of the compressed hops therethrough by opening said head. Compression of the latter is effected by means of a movable head 5 operated by a screw 6 that extends centrally 75 within the drum. The permanently closed head 7 of the drum is moreover provided with passages 8 adapted to be supplied with water from the exterior of the drum and connected interiorly with longitudinally 80 extending sparging pipes 9.

The sleeve 10, through which the material to be operated upon, is introduced into the drum's interior, such sleeve having been previously referred to as of particular interest 85 in the present connection, is held in place between two spaced parallel flanges, or guides 11, that encircle the drum, these flanges with the sleeve being preferably located midway between the ends of the drum 90 so as to facilitate the even distribution of the introduced material within the latter. Said sleeve 10 is preferably constructed of two substantially semi-circular sections, bolted together to facilitate the assembly and 95 taking down of the structure, and is of greater diameter than the drum, having no bearing directly on the latter, but simply a lateral bearing against the inner faces of the respective flanges. An annular chamber is thus formed between the flanges and 100 said sleeve from which the material is admitted to the interior of the drum through openings 12 of proper size formed in the portion of said drum's cylindrical wall lying between said flanges. Packing strips 13 in the outwardly disposed bearing faces of the sleeve (see Fig. 4) insure a tight fit between the sleeve and the flanges.

In order to maintain the sleeve in prop- 110 erly centered relation to the drum, a series of small rollers 14 is provided on each side

of said sleeve, said rollers being disposed so as to track on the outer edges of the respective flanges 11 between which said sleeve is secured. Said rollers are preferably spaced 5 radially with respect to the axis of the drum, so as to leave a certain amount of play between them and said flange edges, as shown in Fig. 1, in order that the sleeve may work backward and forward during 10 the revolution of the press and thus prevent the packing surface from cutting ridges, as would otherwise be apt to occur. The same result may be secured by making the flange edges of slightly eccentric form, thus positively insuring the shifting or backward 15 and forward working of the sleeve. This modification is illustrated in diagrammatic fashion in Fig. 5, where the eccentricity of the flange edge 15 has been exaggerated to 20 make the construction clear.

In addition to the openings 12 in the portion of the cylindrical wall lying between the flanges, through which the material is normally admitted, I provide two slots, 16 25 preferably diametrically oppositely spaced, one on each side of the drum, such slots being of considerably larger area than the openings previously referred to, and extending transversely across the space between the flanges. Adjacent, then, to each of such slots, a deflector plate 17 is secured to the drum, such deflector plate inclining forwardly in the direction of rotation of the drum within the sleeve and being of trans- 30 verse sectional form such as to substantially fill such sleeve. Accordingly, as the drum rotates, these plates gather up any material which may not be passing through the openings 12, and by reason of their inclination, 35 force such material through the slots 16 into the drum's interior. The lower section of the sleeve 10 is, furthermore, provided with a trap door or gate 18 pivoted on a trans- 40 verse axis 19 and normally held closed by 45 means of a winged-nut 20 on a swinging bolt 21. By breaking the connection between the supply pipe 22 and the upper section of the sleeve, and opening this trap door, the entire interior of the sleeve is rendered relatively 50 accessible, at least sufficiently so to permit such obstructions, as will ordinarily occur, to be removed.

It is not deemed necessary to describe the general operation of the press and filter as 55 a whole, while as to the sleeve, that constitutes the feeding connection for the drum, it is believed the foregoing description will render clear its operation as well as its construction. Not only is the sleeve ordinarily 60 maintained clear of the hops by means of the deflectors and adjacent clearing ports, but the interior of said sleeve may be readily got at for cleansing and removal of ob- 65 structions not thus prevented. Furthermore, by the improved mounting provided

for the sleeve the wear between the latter and its supporting flanges is reduced to a minimum and rendered uniform across the bearing faces of the flanges so as to prevent the formation of ridges, which would otherwise speedily result in a leaking joint. 70

Other modes of applying the principle of my invention may be used instead of the one explained, change being made as regards the mechanism herein disclosed, provided the means stated by any of the following claims or the equivalent of such stated means be employed. 75

I therefore particularly point out and distinctly claim as my invention:— 80

1. In apparatus of the class described, the combination with a rotatable receptacle, of connections for supplying to said receptacle the material to be operated upon, said connections including a pair of spaced flanges encircling said receptacle and rotatable therewith, the wall of said receptacle between said flanges having openings for the admission of the material thereto, a sleeve having lateral bearing between said flanges, and an exterior supply connection for said sleeve. 85

2. In apparatus of the class described, the combination with a rotatable receptacle, of connections for supplying to said receptacle the material to be operated upon, said connections including a pair of spaced flanges encircling said receptacle and rotatable therewith, the wall of said receptacle between said flanges having openings for the admission of the material thereto, a sleeve having lateral bearing between said flanges, 90 an exterior supply connection for said sleeve, and rollers carried by said sleeve adapted to bear on the edges of said flanges. 95

3. In apparatus of the class described, the combination with a rotatable receptacle, of connections for supplying to said receptacle the material to be operated upon, said connections including a pair of spaced flanges encircling said receptacle and rotatable therewith, the wall of said receptacle between said flanges having openings for the admission of the material thereto, a sleeve having lateral bearing between said flanges, said sleeve being shiftable between said flanges transversely of said receptacle's axis, and an exterior supply connection for said sleeve. 100

4. In apparatus of the class described, the combination with a rotatable receptacle, of connections for supplying to said receptacle the material to be operated upon, said connections including a pair of spaced flanges encircling said receptacle and rotatable therewith, the wall of said receptacle between said flanges having openings for the admission of the material thereto, a sleeve having lateral bearing between said flanges, said sleeve being shiftable between 105 110 115 120 125 130 135

said receptacle's axis, an exterior supply connection for said sleeve, and rollers carried by said sleeve adapted to bear on the edges of said flanges.

5 5. In apparatus of the class described, the combination of a rotatable receptacle, of connections for supplying to said receptacle the material to be operated upon, said connections including a pair of spaced flanges 10 encircling said receptacle, the wall of said receptacle between said flanges having openings for the admission of the material thereto, a sleeve inclosing the space between said flanges, an exterior supply connection for 15 said sleeve, and means adapted to prevent the accumulation of material within said sleeve.

6. In apparatus of the class described, the combination of a rotatable receptacle, of 20 connections for supplying to said receptacle the material to be operated upon, said connections including a pair of spaced flanges encircling said receptacle, the wall of said receptacle between said flanges having 25 openings for the admission of the material thereto, a sleeve inclosing the space between said flanges, an exterior supply connection for said sleeve, and a deflector plate on said receptacle between said flanges, said plate 30 gather up any accumulation of material within said sleeve.

7. In apparatus of the class described, the combination of a rotatable receptacle, of 35 connections for supplying to said receptacle the material to be operated upon, said connections including a pair of spaced flanges encircling said receptacle, the wall of said receptacle between said flanges having 40 openings for the admission of the material thereto, a sleeve inclosing the space between said flanges, an exterior supply connection for said sleeve, and a deflector plate on said receptacle between said flanges adapted to

gather up any accumulation of material within said sleeve, a slot, larger than the 45 aforesaid openings, being formed in the receptacle's wall adjacent to said deflector plate.

8. In apparatus of the class described, the combination of a rotatable receptacle, of 50 connections for supplying to said receptacle the material to be operated upon, said connections including a pair of spaced flanges encircling said receptacle, the wall of said receptacle between said flanges having 55 openings for the admission of the material thereto, a sleeve inclosing the space between said flanges, an exterior supply connection for said sleeve, and a deflector plate on said receptacle between said flanges, said plate 60 inclining forwardly in the direction of rotation of said receptacle and being adapted to gather up any accumulation of material within said sleeve, a slot, larger than the 65 aforesaid openings, being formed in the receptacle's wall in front of said deflector plate.

9. In apparatus of the class described, the combination of a rotatable receptacle, of 70 connections for supplying to said receptacle the material to be operated upon, said connections including a pair of spaced flanges encircling said receptacle, the wall of said receptacle between said flanges having 75 openings for the admission of the material thereto, a sleeve inclosing the space between said flanges, an exterior supply connection for said sleeve, and a gate into said sleeve at a point substantially opposite to 80 said supply connection.

Signed by me this 22nd day of Sept., 1911.

ADOLPH GLASER HUPFEL.
